UNITED STATES PATENT OFFICE.

ROBERT P. BARNSTEAD, OF BOSTON, MASSACHUSETTS.

VALVE.

1,140,653.

Specification of Letters Patent. Patented May 25, 1915.

Application filed November 12, 1914. Serial No. 871,830.

To all whom it may concern:

Be it known that I, ROBERT P. BARNSTEAD, a citizen of the United States, and a resident of Boston, in the county of Suffolk and 5 Commonwealth of Massachusetts, have invented certain new and useful Improvements in Valves, of which the following is a full, clear, and exact specification.

This invention relates to that type of 10 valves for supplying drinking water under pressure, wherein a push valve is connected with laterally extended arms up against which is pressed the cup or glass to be filled, for the purpose of opening the valve and 15 filling such cup or glass. Among other difficulties found to exist in connection with this form of valves is, first, a failure of the valve so to seat itself that the water will be wholly shut off and will not continue to drip; 20 second, when the presser arms are elevated suddenly the delivery of the water is liable to be so violent as to spatter itself out from the cup or glass upon the hand or even the cuff of the person operating the same.

25 The object of this invention is the construction of a valve of the above-named type, which shall not only be free of said defects, but shall possess other advantages herein- 30 after set forth and illustrated in the accompanying drawings, wherein—

Figure 1 is a side and sectional elevation of a valve embodying my improvements. Fig. 2 is a top view of the actuating device. Fig. 3 is a horizontal section of the device 35 mainly depended upon for overcoming the violent delivery of the water. Fig. 4 is a face view of the valve-seat member. Fig. 5 is a face view of a device provided for further assuring against the violent delivery 40 of the water and the consequent spattering thereof.

The reference numeral 1 designates the water pipe supplying the water under pressure of from forty to eighty pounds per 45 square inch, as is found in the city mains, and 2 is the well-known two-armed valve-operating plunger.

The valve proper 3 is made the head of a slender post comprising a neck 4, a shoulder 5, and a body 6 adapted to be screwed into 50 the end of the plunger 2. I have found that the head or valve 3 must be quite small in diameter in order to be raised with sufficient ease against the above-recited heavy water-pressure, for a half inch valve would receive 55 upon its nearly one-fourth of a square inch

of surface a pressure of twenty pounds, in the case of the eighty-pound water-main, and no one could be able to force a cup or glass upward against the valve-arms sufficiently hard to open the valve, without danger of breaking such cup or glass. But, by reducing the valve to a quarter of an inch in diameter, the area is reduced to a sixteenth of a square inch, and the pressure to 60 be overcome is consequently but one-sixteenth of 80, or but five pounds.

The seat for this valve is a washer 7, preferably composed of compressed fiber or hard-rubber, having its central opening 9 70 somewhat smaller than the valve, but considerably larger than the neck 4, and just large enough to permit the shoulder 5 to easily enter it.

When the post is elevated, as by an upward pressure applied to the arms 10, the water passes through the opening 9, about the neck 4, and thence downward between the ribs 11 of the plunger 2 into the cup or glass beneath. To prevent the water thus 75 delivered from coming with undue force and thus spraying or spattering itself upon the person holding the drinking glass, I provide means for so hindering the flow as to give a slow moving but large stream capable of 80 filling the glass quickly but without danger of loss. In accomplishing this, I first provide a tortuous passage formed by a spool whose upper flange 12 is imperforate, but 85 whose lower flange 13 is formed with numerous holes 14, as is also its tubular body 15 with radial holes 16. When the valve rises above its seat 7, the shoulder 5 enters the interior opening of said spool and so closes all 90 outlets except the tortuous ones through the holes 14 and 16. While this accomplishes 95 good results where the water-pressure is comparatively low, yet for high-pressure mains, I find it necessary to mount upon the post-body 6 between the shoulder 5 and the top of the plunger 2, a small rotative fan 17, whose vanes 19 are sufficiently twisted to cause their rotation under the action of the water, Fig. 5. Hence, in case the flow has

100 not been sufficiently retarded by the spool, 105 this rotating fan effectually brings the same down to the slow speed needed in use.

The washer 7 is held in place upon the top flange 12 within the upper part of the member or valve case 20 by the shoulder 21 which 110 is fixed within the T 22. When the latter member 22 is screwed down within the valve

case 20, the shoulder seats upon the washer 7 and retains it firmly in position.

For keeping the valve and plunger from rising so high under the glass-filling pressure that the fan 17 would meet the spool-flange 13 and be kept from rotation, and possibly flattened out, I provide means, as the arch 23 extended radially across the upper part of the shoulder 21, against which the valve 3 may contact and so limit the rise of the plunger.

Whenever the washer becomes worn and incapable of water-tight engagement with the valve 3, the valve case 20 is unscrewed from the T, the valve post is unscrewed from the plunger 2 and withdrawn from the spool, the old washer is removed from the post, a new washer 7 is substituted, and the other parts restored to their original positions.

Previous to my invention, the plunger 2 was sufficiently smaller than the interior of the nozzle 24 to permit the unimpeded passage of the water, and was without the vertical ribs 11. The difficulty with such construction was that a strong pressure applied

to one alone of the arms 10 was sure either to break or bend the post 6, but by forming the plunger with the ribs 11, as shown in Fig. 2, such breaking and bending is prevented, since the ribs fit slidably within the nozzle.

What I claim is:

A valve comprising a casing, a spool therein having radial openings through its body and openings in its lower flange, a valve opening and seat above said spool, a slender post having a head larger than the valve opening and coöperating therewith, a neck smaller than the interior of the spool and a body portion fitted to enter said interior, and means for raising said post to put said head out of engagement with said valve opening.

In testimony that I claim the foregoing invention, I have hereunto set my hand this 7th day of November, 1914.

ROBERT P. BARNSTEAD.
